UNITED STATES PATENT OFFICE

MATHIAS BERING BRÝLD, OF HORSENS, DENMARK.

SOFA OR ARMCHAIR THAT CAN BE CONVERTED TO A BED.

1,359,027.

Specification of Letters Patent. Patented Nov. 16, 1920.

Application filed July 8, 1920. Serial No. 394,720.

To all whom it may concern:

Be it known that I, MATHIAS BERING BRÝLD, director, a citizen of Denmark, residing at Horsens, Torvet Nr. 7, a subject of the King of Denmark, have invented a new and useful Sofa or Armchair that Can be Converted to a Bed, of which the following is a specification.

My invention has reference to a sofa or 10 an armchair that can be converted to a bed. The distinguishing feature of my invention is that, when a special lock-mechanism is released, the seat of the sofa or the armchair, influenced by springs, is automatically 15 pushed forward, whereby the part of the seat that is normally placed under the back of the sofa or the armchair becomes usable as a bed. Between the back-edge of the movable seat and the back of the piece of furniture in question a coarse cloth is stretched out, which, when the seat is pushed forward, is tightly stretched flush with the top of the seat, whereby the area, used as a bed, is enlarged.

25 My invention will now be described with reference to the accompanying drawing, in which—

Figure 1 is a perpendicular section through a sofa with the seat pushed forward, so that it can be used as a bed;

30 Fig. 2 is the same drawing with the seat of the sofa in its normal position;

Fig. 3 is the sofa seen in front partly sectionally;

35 Fig. 4 is a fragmentary sectional view;

Fig. 5 is a perpendicular section of an armchair, and

Fig. 6 is the same converted to a bed.

An additional style of constructions is 40 illustrated in the Figs. 7-9, in which—

Fig. 7 is part of a sofa seen from the top;

Fig. 8 the same seen in front; and

Fig. 9 the same with the back let down.

Similar letters refer to similar parts 45 throughout the several views.

As shown in Figs. 1-4 the substructure of the sofa consists of a frame 5, supported by legs 6. To the frame 5 is secured a sofa-back 9. At each end of the frame 5 is a board 10, 50 on which the seat 11 of the sofa can slide, while being moved backward and forward.

The seat 11 has two arms 7 and 8 and consists of a frame 12 of boards on edge, over

which there is expanded a stuffed cover 13. From the seat 11 there go out two downward projections 14, between which and the back of the frame 5 some springs 15 are compressed, which seek to push the seat of the sofa forward, that is to say away from the back of the sofa.

55 To the front side of the frame 5 there is secured a lock-mechanism consisting of two bars 16. The bars 16 can be turned on their respective gudgeons 17, and each of them has at its very end a pin 18, which normally juts 60 into a hole in the under side of the sofa-seat 11. To one of the bars 16 is secured a little plate 19, which passes under the other bar so that both bars can be turned at the same time, when for instance you lift the plate 19 65 by your tiptoe. Over each of the bars 16 there is fitted a spring 20, which seeks to cause the bars to occupy the position, shown in Fig. 3, where the pins 18 are in engagement with the holes set apart for them in the 70 sofa-seat 11.

The arms 7 and 8 are shown without stuffing. The arm 8 is fast, whereas the arm 7, when lifted a little, can be let down to the position 7', shown in Fig. 3, a hinge 21 being 80 fitted at its bottom edge, (see Fig. 4).

As before said, it is necessary to lift the arm a little, so that a key on a ledge 28 of the arm can go clear of a corresponding slot in a ledge 29, which is fitted in fast connection with the seat 11.

Instead of the key and the slot, of course, a pin on the ledge 28 and a corresponding mortise in the ledge 29 can be used.

85 A chain 22, Fig. 3, keeps the arm in its sloping position. The hinge 21 can be a double hinge, as shown in Fig. 4, with one hinge-link 23, so that the arm, when lifted and then let down, can occupy the position 7" shown in Fig. 3, where the arm is nearly 90 perpendicular.

The back we might use as a cupboard, its upper and foremost wall being formed by a flap that can be turned on a hinge 24. A board 25 forms the bottom of the cupboard. 100

Under the sofa is a chest 26, covered with a piece of canvas 27, or the like. This extends between the foremost upper edge of the chest 26 and the hindmost lower edge of the sofa-seat, so that it is removed automatically, when the sofa-seat is pushed forward; 105

or is caused to cover the chest 26, when the sofa-seat is pushed back to the position, shown in Fig. 2. The said chest can be used as a depository of bed-clothes.

- 5 To the upper and hindmost edge of the sofa-seat 11 there is secured a coarse cloth 30, the opposite side of which is removably secured to the back of the sofa by means of clasps (see Fig. 1), when the seat is pushed 10 quite forward, the cloth is tightly stretched flush with the top of the seat, and can form a comfortable bed, for instance for a child.

At the fore-side of the sofa-seat there are feet 31 that can be turned.

- 15 As shown in Fig. 1 to the sofa-back there is secured a pivot 32, which normally juts into a hole 33 in the back-piece of the arm 7, so that the arm is firmly held in place, when the piece of furniture is used as a sofa; but when used as a bed, the arm can be lifted and turned easily.

The stuffing of the back 9 consists of springs 34, which alternately with short pieces of hoops are stretched between the 25 two side-pieces of the back-flap. Thus a good and cheap structure is obtained together with spaciousness in the cupboard, formed by the sofa-back.

The sofa works as follows:

- 30 In Fig. 2, when you lift the plate 19 by your tiptoe, the pins 18 are drawn out of the holes in the under side of the sofa-seat, and this is then, influenced by the tightened springs 15, pushed forward to the position, shown in Fig. 1, and the sofa can now be locked in a proper manner. Then the arm 7 is let down, and the sofa-seat together with the cloth 30 can now be used as a bed. When the bed again is to be converted to a sofa, the arm 7 is passed back to its normal position, and the sofa-seat is pushed back to the position shown in Fig. 2, where the pins 18, influenced by the springs 20, of their own accord move into their respective holes in the under side of the sofa-seat, whereby this is locked.

As shown in Figs. 5 and 6 the piece of furniture mentioned can also be constructed as an armchair that can be converted to a bed.

- The armchair consists of a loose seat 35, supported by the substructure 36 of the chair. 37 is the stuffed back of the chair, supported by two arms 38, which can turn 55 on gudgeons 39. 40 is the arm of the chair. The seat 35 is held in place, just as the sofa-seat 11 mentioned above, by some lock mechanism, and when this is released, the seat is passed forward to the position shown in Fig. 6, influenced by springs, which for instance can be located hidden under the arms.

The seat has as its front edge two feet 41 that can be turned. The back 37 is then turned backward to the position, shown in

Fig. 6, where it serves as a bolster, and a coarse cloth 44 expanded between the foremost edge 42 of the back 37 and the hindmost edge 43 of the seat 35 now forms the necessary connection between the bolster and the seat 35.

The arms 40 are in the shown style of construction secured to the substructure 36 of the chair, but they can also be secured to the seat 35 and take part in its ahead motion.

The site of the gudgeon 39 is of but little consequence, if only the coarse cloth 44 will be in a line with the top of the seat 35. The interior of both the back and the arms can be used as depositories of bed-clothes for instance.

The abovementioned sofa can also be built on the same principle as the armchair, so that the sleepers will be lying with the head toward the back of the sofa, and the legs at the fore-side of the sofa-seat.

In the abovementioned sofa, which can be converted to a bed, we have conceived the arms to be placed perpendicular to the back of the sofa. With certain types of furniture, however, this is not the case; these types have their arms at an angle to the back of the sofa, or the arms take the form of a bow, and form a direct continuation of the sofa-back, so that it is impossible to see an abrupt transition between the back of the sofa and the arm.

When such a slanting or curved arm is let down in order to form a bolster of a bed, the position of the bolster will become very inconvenient for the sleeper.

The peculiar feature of the invention now is that the arm is so connected with the substructure or the seat of the sofa that it turns on a perpendicular axis, at the same time as it is let down to a slanting position, so that it, in this position, will be situated in the correct proportion to the seat of the sofa.

The substructure *a* (see Figs. 7-9) of the sofa supports the sofa-seat *b*, the back *c* and the arm *d*.

To the substructure *a* there is secured a perpendicular pivot *e*, on which an iron-strap *f* can turn. The arm *d* is by means of hinges *g* and *h* secured turnable to this strap, and by two or three chains *i* and *k* connected with the substructure and the back of the sofa.

When the arm *d* is let down to serve as a bolster, the strap *f* will, of its own accord, turn on the pivot *e* to the position *f'*, in which the chains *i* and *k* are tightly stretched. Consequently, by varying the length of the chains the arm *d* can be so adjusted, that, in its slanting position, it is situated opposite the sofa-seat *b*, and has a correct inclination in proportion to the same. The triangular space between the arm and the sofa-seat can be covered with a

coarse cloth, sewn on these objects, a cloth that unfolds itself of its own accord, when the arm is let down.

The hinges *g* and *h* can have several joints, as shown in Fig. 9, so that the arm obtains an easier motion in relation to the strap *f*.

I claim:

1. A piece of convertible furniture comprising a slideable seat, hingedly mounted arms, a back, a frame slidably supporting said seat, means on said back coöperating with said arms to retain them in vertical position, said means being disconnected when said seat is moved away from said back, substantially as described.

2. A device of the class described comprising a slideable seat, a frame slidably supporting said seat, arms pivotally mounted upon said seat and movable therewith, a back, pins projecting from said back, said arms being formed with apertures, said pins and apertures coöperating to retain said arms in vertical position, said arms being adapted to move away from said back and be released therefrom when said seat is

forced to its extended position, substantially as described.

3. A device of the class described comprising a frame, a slideably mounted seat supported on said frame, a back, arms, a pivotally mounted strap, and means for hingedly securing said arms to said strap, substantially as described.

4. A device of the class described which comprises a frame, a slideably mounted seat supported on said frame, a back mounted rigidly with respect to said frame, arms, straps pivotally mounted and capable of swinging horizontally, means for pivoting said arms to said straps, said arms being movable with said seat and means on the back coöperating with said arms to retain them substantially vertical when the seat is in retracted position.

The foregoing specification signed at Aarhus, Denmark, this seventeenth day of June, 1920.

MATHIAS BERING BRYLD.
